UNITED STATES PATENT OFFICE.

ANDREW ROSENTHAL, OF NEW YORK, N. Y.

FAUCET WATER-MIXER.

1,214,221.

Specification of Letters Patent. Patented Jan. 30, 1917.

Application filed May 4, 1916. Serial No. 95,436.

To all whom it may concern:

Be it known that I, ANDREW ROSENTHAL, a citizen of the United States, and a resident of the city of New York, borough of 5 Manhattan, in the county and State of New York, have invented a new and Improved Faucet Water-Mixer, of which the following is a full, clear, and exact description.

Among the principal objects which the 10 present invention has in view are: to provide a device for mixing water of different temperatures preliminary to delivering the tempered water for use; and to provide an attachment of the character mentioned having a simplified and cheapened construction.

Drawings.—Figure 1 is a front elevation of a mixer constructed and arranged in accordance with the present invention, the same being shown as in service; Fig. 2 is a 20 top plan view of the same; Fig. 3 is a vertical cross section taken as on the line 3—3 in Fig. 1.

Description.—The chief employment of a mixer constructed and arranged as herein 25 described and as shown in the accompanying drawings, is to permit the dish-washer to mix hot and cold water received from the respective faucets with which sinks are provided, prior to delivering the same to a 30 dish pan or receptacle. With this object in view, two clip plates 8 are furnished, the ends of the plates having formed therein ovoid openings 9. The contracted ends of the openings 9 are turned away from the 35 extensions 10 with which the plates 8 are provided. At the extremities of the extensions 10 are formed perforations 11, which are provided to receive the hook ends 12 of a connecting spring 13. The spring 13 provides for an expansion of the plates 8 when 40 adjusting the mixer in service, and when the nozzles 14 of faucets extend through the openings 9, to be gripped by the contracted ends thereof.

45 The mixing trough 15 is suspended from the fixture above described, by means of a hanger 16. The hanger 16 is constructed from a single piece of metal to form a loop, the inner diameter or opening whereof is 50 shaped to the cylinder of the coil of the spring 13. From the loop a strap 17 is twisted and is integral with a bridge piece 18, the ends whereof are outturned for sol-

dering the bridge piece in service relation to the trough 15, as seen best in Figs. 2 and 55 3 of the drawings. The bridge piece 18 is placed at the center of the trough 15 to balance the same. Disposed directly beneath the bridge piece 18, and at the center of the trough 15, is a spout 20. The lower edge of 60 the spout 20 is inturned to support a flange 21 for supporting a sieve 22.

When water is to be drawn for washing dishes, or for any other purpose, the mixer is adjusted on the nozzles 14 of the faucets 65 by the person using the same. The plates 8 are spread, and the spring 13 extended until the broad portions of the openings 9 are in register with and permit the passage thereof of said nozzles. The spring 13 70 draws inward the plates 8 with sufficient force to grip the said nozzles within the contracted ends of the openings 9. This operation is preferably effected prior to installing the trough 15. Having adjusted the spring 75 13 and plates 8, the trough 15 is placed in position, the loop of the hanger 16 being passed over the body of the spring 13, when it will be found that the ends of the trough 15 rest below and in line with the nozzles 14, 80 to receive the water when permitted to pass therefrom.

The water received in the trough 15 is delivered therefrom through the spout 20. It is obvious that the operator may temper the 85 water to suit, by admitting more or less of hot or cold water to the trough 15. The water thus tempered is delivered by way of the spout 20 to the dish pan or other receptacle, the sieve 22 operating to arrest the 90 passage of any detritus which may be in the water when delivered by the faucets to the trough 15.

Claims:

1. A faucet water mixer comprising an 95 elongated trough having end extensions to lie below the faucets of the usual water supply fixture, said trough having a central delivery opening; and means for removably attaching the trough in service, said means 100 embodying an extension spring, and clip plates pivotally attached to the ends of said spring and having ovoid openings formed therein, the contracted ends of said openings being extended away from said spring. 105
2. A faucet water mixer comprising an

elongated trough having end extensions to lie below the faucets of the usual water supply fixture, said trough having a central delivery opening; means for removably attaching the trough in service, said means embodying an extension spring, and clip plates pivotally attached to the ends of said

spring and having ovoid openings formed therein, the contracted ends of said openings being extended away from said spring; and a hanger permanently mounted on said trough for removably engaging said spring.

ANDREW ROSENTHAL.
